United States Patent

Des. 236,037
Patented July 22, 1975

236,037

WRIST PURSE OR SIMILAR ARTICLE

Joseph J. McCarthy, Saugus, Mass.
(21 Berwick, Melrose, Mass. 02176)

Filed May 30, 1973, Ser. No. 365,081

Term of patent 14 years

Int. Cl. D5—06

U.S. Cl. D87—3 B

FIG. 1

FIG. 2

FIG. 3

FIG. 4

FIG. 5

FIG. 1 is a perspective view of a wrist purse or similar article showing my new design;

FIG. 2 is a top plan view thereof;

FIG. 3 is a bottom plan view;

FIG. 4 is an end elevational view; and

FIG. 5 is a perspective view in an open position.

I claim:

The ornamental design for a wrist purse or similar article, substantially as shown.
